UNITED STATES PATENT OFFICE.

JAMES D. HAUGHTON AND WILLIAM J. ALEXANDER, OF MONROE COUNTY,
(NEAR EGYPT, CHICKASAW COUNTY,) MISSISSIPPI.

BALING-PRESS.

SPECIFICATION forming part of Letters Patent No. 379,645, dated March 20, 1888.

Application filed December 7, 1887. Serial No. 257,239. (No model.)

To all whom it may concern:

Be it known that we, JAMES D. HAUGHTON and WILLIAM J. ALEXANDER, citizens of the United States, residing in Monroe county, near 5 Egypt, in Chickasaw county, and State of Mississippi, have invented a new and useful Improvement in Baling - Presses, of which the following is a specification.

The invention relates to improvements in 10 baling - presses, being especially adapted to press hay; and it consists in the construction and novel combination of parts hereinafter described, illustrated in the drawings, and pointed out in the claims hereto appended:

15 In the accompanying drawings, Figure 1 represents a side view of a press embodying the invention and attached to a wagon. Fig. 2 is a plan view of the same. Fig. 3 is a central vertical longitudinal section of the parts. 20 Fig. 4 is a sectional view on the line *x x*, Fig. 2. Fig. 5 is a perspective view of the platen and attached anti-friction wheels.

Referring to the drawings by letter, A designates the long rectangular main frame of 25 the machine, with the press-frame B rising from it near its front end, and having the flanged ways *a a'* formed on the upper surface of its side beams in rear of the press-frame. The press-frame is provided with the 30 top frames, *b b'*, parallel to the side beams of the main frame, and the vertical beams *b' b'*, connecting said side beams and top beams.

C is the head of the press, secured in the front end of the press-frame and provided in 35 its rear or inner surface with the vertical grooves or kerfs *c*, for the passage of the tying-wires or suitable bale-ties.

The top of the press-frame, between its side and end beams, consists of a door, D, connected by hinges *d* to one side beam and held closed by a suitable number of buttons, *d'*, pivoted to the opposite side beam. The said door is preferably composed of longitudinal slats and transverse rails secured thereon, and 45 upon which the buttons *d'* engage.

The bottom of the press-frame is provided with the cross-beams *e e'*, between the front two of which is the door E, hinged at its rear edge to the adjoining beam, *e*, and held closed 50 at its front edge by the buttons *e'*, hinged to the front beam, *e*, as shown in Fig. 3.

F is a depending metal loop, secured cen-

trally to one of the cross-beams *e*, near the rear of the press-frame, and *f* is a metal bar pivoted at its rear end on the front beam, *e*, 55 and having the opening *f'* near its front end.

The door E is composed of longitudinal slats and cross-bars similar to those of the top door, and the part of the bottom in rear of the door has similar longitudinal slats secured 60 to the inner or upper sides of the beams *e*.

Between the two beams *b' b'*, at the front of the press-frame on each side, is the swinging door G, hinged at its upper edge to the corresponding top beam of the press-frame and 65 held closed at its lower edge by the buttons *g*, pivoted to the side beam of the main frame. The said doors are somewhat narrower between the beams *b'* than the bottom door is between its corresponding beams, and are provided with similar longitudinal slats, the sides 70 of the press-frame in rear of the doors G being also provided with the same.

The front and rear ends of the press-frame are braced on the side beams of the main frame 75 by suitable inclined stay-rods, as shown in the drawings.

H is the platen or follower-plate, provided with the vertical grooves or kerfs *h*, corresponding with and opposite to those in the 80 head C. The platen is notched rectangularly at each lower corner, as at *h'*, and in such notched portions are journaled to the edge of the platen the anti - friction wheels, which move on the bottom slats, *h' h'*, adjoining the 85 side beams of the main frame, which slats form ways for said wheels.

i i are longitudinal bars extending rearward from the platen to the driver-bar *I*.

j j are studs depending from the ends of said 90 driver-bar and having journaled upon them the anti-friction wheels *J J*, which move over the ways *a a'*, and *k* is an eyebolt secured centrally to the front side of the driver-bar between the bars *i*. Upon the said eyebolt is swung 95 the double-sheaved block K.

l is a strong vertical metal rod secured centrally between the top and bottom cross-beams at the rear end of the press-frame, and *L* is a single-sheaved block secured to a suitable 100 point of said rod.

M is a windlass having its transverse shaft, *m*, journaled in bearings secured to upper surfaces of the side beams of the main frame im-

mediately in rear of the press-frame, the said shaft being below the bars *i*. The shaft *m* has on its respective ends the wheels *O* and *P*, each provided with a series of equidistant outstanding handles, *o o*, by means of which two workmen—one on each side—can operate the windlass. The wheel *O* has a flat periphery to receive a band from a steam or other motor, and the wheel *P* has a grooved periphery in which to actuate and wind a rope having a horse hitched at the other end. Thus the machine can be run by hand, horse, or steam power.

Q is a rope, preferably of wire, having one end secured to the vertical bar *l*, running thence rearward and around one of the sheaves of the double block *K*, then forward around the sheaves of the single block, then again rearward around the second sheaves of the double block, and then forward to have its other end secured to the shaft of the windlass. The power is thus multiplied, in the well-understood manner, both by the leverage of the wheels and by the movable pulleys.

25 To attach the machine to a wagon, the king-bolt is withdrawn therefrom, separating the reach from the front axle and detaching the tongue. The reach *R* is then passed through the metal loop *F*, secured to the bottom of the machine, and the king-bolt *S* is passed through the opening in the bar *f* and its seat in front axle.

To use the machine, the bottom and side doors are closed by the means described, the upper door opened, the platen run to the front of the press, and the hay introduced in the frame. The upper door is then closed and the platen pushed into the press by the described means. When the hay is fully compressed, the brake *T* is turned upon the adjoining wheel of the windlass, the upper and lower doors are opened, and the tying-wires or bail-ties are passed through the kerfs or grooves in the platen and bed, and the bale completed. When 45 the platen is again drawn rearward, the bale may be dropped out of the bottom door.

By the described machine, properly constructed, one hundred pounds of hay can be quickly and easily compressed into a bale 50 eighteen inches square.

The machine, if desired, may be mounted on suitable supports—such as trestles—instead of a wagon; but its use in connection with a wagon, as described, is very handy and economical for farmers, all of whom have wagons 55 of about the same description.

Having thus described our invention, we claim—

1. A baling-press comprising the main frame, the press-frame having the head provided with vertical grooves at its rear end, the hinged top door extending its entire length, the hinged bottom door adjoining said head, and the hinged side doors adjoining the head 65 and narrower than the bottom door, and the flanged ways formed on the side rails of the main frame in front of the press-frame, of the

vertically-grooved platen, notched at its lower corners, the drive-bar, the longitudinal bars connecting the platen and the drive-bar, the anti-friction wheels connected to the drive-bar and the platen, the windlass journaled at the front of the press-frame, the central vertical metal bar secured in the front end of said frame, the double-sheaved block attached to the drive-bar, the single-sheaved blocks attached to the vertical metal rod, and the rope connecting the said rod and the windlass and running over the sheaves of said blocks, substantially as specified. 80

2. In a baling-press, the combination, with the main frame, the press-frame, the head at the rear end thereof, and the flanged ways in front of the press-frame, of the platen, the drive-bar connected thereto by longitudinal bars, the anti-friction wheels connected to the platen and the drive-bar, the sheaved blocks, the actuating-rope and the windlass consisting of the transverse shaft, and the wheels *O* and *P* thereon, each provided with a series of equidistant outstanding handles, *o*, the wheel *O* being smooth on its periphery to receive a belt from a motor, and the wheel *P* having a grooved periphery in which to attach and wind an actuating-rope, substantially as specified. 95

3. A baling-press comprising the main frame, press-frame, head, platen, and mechanism, substantially as described, whereby the platen is operated, of the metal loop secured to the bottom of the main frame in front of the bale-discharge opening of the press-frame to receive the reach of a wagon tongue and reach of which have been separated from the front axle, and the metal arm secured to the bottom of the main frame in rear of said discharge opening, and provided in its rear end with an opening to receive the king-bolt of said wagon and by means of said bolt attach the machine to the separated front axle of the wagon, substantially as specified. 100

4. In a baling-press, the combination, with the main frame, the press-frame having the head, and the ways formed on the side rails of the main frame in front of the press-frame, of the platen, the drive-bar, the longitudinal bars connecting the platen and the drive-bar, the anti-friction wheels connected to the drive-bar and the platen, the windlass journaled at the front of the press-frame, the double-sheaved block *K*, attached to the drive-bar, the single-sheaved blocks *L*, and the rope connecting the windlass and running over the sheaves of said blocks, substantially as specified. 115

In testimony that we claim the foregoing as our own we have hereto affixed our signatures in presence of two witnessess.

JAMES D. HAUGHTON.

WILLIAM J. ALEXANDER.
